UNITED STATES PATENT OFFICE.

HENRY A. PETER, OF PHILADELPHIA, PENNSYLVANIA, ASSIGNOR TO PIONEER SUSPENDER COMPANY, A CORPORATION OF PENNSYLVANIA.

DISPLAY BOX AND SUPPORTING ELEMENT FOR SUSPENDERS.

Application filed January 30, 1925. Serial No. 5,714.

My invention relates to display boxes for suspenders. The object is to provide an improved box or container for holding a pair of suspenders for purposes of transportation and also for display.

The invention comprises a box and a telescoping lid therefor; the box provided with partial covering portions adjacent the two ends and extending a comparatively short distance therefrom along the top margins of the side portions; the box in other respects being open as to one side. The purpose is to leave the box open entirely from one longitudinal side portion to the other longitudinal side portion, so that the two free ends of the suspender will be exposed to view from side to side; that is to say, the width of the box is slightly greater than the width of two suspender straps so that there will be no overhanging portions on the two longitudinal sides. In combination with this there is provided a supporting element such as a card adapted to fit within the box, being slightly narrower and slightly shorter than the inside of the box. Upon this element the suspenders are detachably secured by any suitable means, and the ends of the supporting element, together with the suspenders secured thereto, are inserted beneath the partial covering portions as herein shown.

Referring to the drawings, which illustrate, merely by way of example, a suitable embodiment of my invention:

Fig. 1 is a perspective view showing the method of inserting the suspenders and the supporting element into the box.

Fig. 2 is a longitudinal section of the box with the suspenders therein and the telescoping lid or cover closing the open part thereof.

Similar numerals refer to similar parts throughout the several views.

The box 3 is preferably of rectangular formation, long, narrow and shallow, adapted to accommodate one pair of suspenders 4, folded about a supporting element 5, as shown. The suspenders are removably se-

cured to the supporting element 5 by any suitable means, such as the band 6. The box 3 is provided with the partial covering portions 7. These portions 7 are shown as extending from the two opposite ends of the box, the entire width of the box, a comparatively short distance from said ends, and engaging throughout said distance with the side portions or walls of the box. When inserting the supporting element, with the suspenders secured thereto, the element is bent or flexed as indicated in Fig. 1, so that the ends may be inserted beneath the partial covering portions 7, and then, when the supporting element is flattened out, it will lie substantially the entire length of the box, with the major portion of the front part of the suspenders fully exposed to view. A telescoping lid or cover 8 is provided for closing the open portion of the box, for transportation. This lid may be entirely removed, or it may be positioned about the under portion of the box for display.

What I claim is:

The combination of a display box and supporting element for suspenders, comprising a container having bottom, side and end portions, and top portions permanently secured to the end portions and extending therefrom a relatively short distance and secured along said extensions to the top edges of the side portions, a flexible supporting element corresponding approximately in dimensions with the dimensions of the bottom portion within the box, said supporting element provided with a pair of suspenders extending longitudinally around said supporting element with retaining means for securing the suspenders in said position with respect to the supporting element, said supporting element adapted to be flexed in order to introduce the ends thereof, with the suspenders supported thereby, beneath the said short extensions and then to assume the flat position, as and for the purpose described.

HENRY A. PETER.
